UNITED STATES PATENT OFFICE.

CESARE BARBIERI, OF NEW YORK, N. Y., ASSIGNOR TO THE VORTEX MFG. CO., OF CHICAGO, ILLINOIS, A CORPORATION OF ILLINOIS.

NESTED-FLAT-CUP DISPENSER.

Application filed September 26, 1924. Serial No. 739,979.

This invention relates to a paper cup dispenser and more particularly to a dispenser wherein flat superimposed nested cups are deposited on a spring impelled support within a container with the apex of the uppermost cup projecting through a slotted cover to permit ready access to the apex of the cup whereby the uppermost cup may be easily withdrawn from the container through the slotted cover.

It is an object of this invention to provide a dispenser wherein superimposed nested cups are automatically fed upwardly in a container each time a cup is withdrawn.

It is also an object of this invention to provide a container wherein flat nested cups are deposited within a container upon a spring impelled movable support which acts to hold the top of the uppermost cup projected into a position wherein the same may be readily grasped by the fingers of an operator and withdrawn from the container.

It is a further object of this invention to provide a dispenser wherein a spring supported holder is adapted to automatically feed nested flat cups upwardly between suitable guides into a slotted cover from which the cups may be withdrawn one at a time.

It is an important object of this invention to provide an improved flat cup dispenser of simple and inexpensive construction adapted to automatically feed flat nested cups into a position within a cover from which the cups may be manually extracted as desired.

Other and further important objects of this invention will be apparent from the disclosures in the specification and the accompanying drawings.

This invention (in a preferred form) is illustrated in the drawings and hereinafter more fully described.

On the drawings:

Figure 1 is a front elevation of a nested flat cup dispenser embodying the principles of this invention.

Figure 2 is a side elevation thereof.

Figure 3 is a longitudinal section of the dispenser taken on the line 3-3 of Figure 2 with parts shown in elevation.

Figure 4 is a top plan view of the dispenser.

Figure 5 is an interior view of the dispenser cover.

Figure 6 is an enlarged top plan view of

the dispenser with the cover in open position and broken away and further illustrating a stack of cups within the container.

Figure 7 is a top plan view of the dispenser with the cover removed illustrating the cup support in position ready to receive a stack of nested cups.

Figure 8 is a fragmentary detail section taken on the line 8-8 of Figure 1 with the supporting spring omitted.

65

As shown on the drawings:

The reference numeral 1 indicates a container of elliptical cross section having flat side walls and convex front and rear walls. Secured or integrally formed on the upper end of the container rear wall is a stop plate 2. The side walls of the container extend rearwardly to form side plates 3 the rear margins of which are bent outwardly at an angle to form mounting flanges 4 which may be apertured or slotted to permit the container to be mounted on a wall or other support. Pivotedly mounted by means of a hinge 5 on the upper end of one of the flat side walls of the container 1 is a cover 6 in the shape of the frustum of an elliptical cone. The cover 6 is provided with a cup discharge or outlet slot 7 the middle of said slot at the upper end of the cover being enlarged to afford front and rear notches 8 to permit the fingers of an operator to engage the projecting tip end of a paper cup to remove the cup from the container through the slotted cover.

A stack of flat nested cups 9 is adapted to be placed within the container when the cover is open. The cups 9 are positioned with the tips thereof directed upwardly with the lowermost cup seating upon an elliptical holder or form 10 which is pivotally mounted upon the upper end of a piston or plunger 11. The plunger 11 is slidably mounted within the container 1 and is shaped to conform to the contour of the interior of said container. The plunger 11 is resiliently supported on the upper end of a spiral strap or band spring 12 as illustrated in Figure 3. The lower end of the spring 12 rests upon a plate 13 which is mounted within the container 1 upon the container base or bottom 14. The stack of cups 9 within the container is positioned to pass between a pair of notched guides 15 which are mounted within the container near the upper ends of the container side walls. The 110

cover 6 is adapted to be held in closed position upon the top of the container 1 by means of a lock 16 or other suitable means. Mounted within the cover 6 on opposite sides of the ends of the slot 7 are felt pads 17 as illustrated in Figure 5.

The operation is as follows:

The dispenser is adapted to be mounted on a wall or support by securing the mounting flanges 4 upon the wall by means of screws or other suitable means. If desired the dispenser may be positioned to stand upon a desk or other support. By removing the lock 16 the cover 6 may be swung into open position. When the container is open the spring 12 acting upwardly on the plunger 11 pushes the elliptical holder 10 into its upper position with the ends of said holder engaged against the stops or guides 15. The stops or guides 15 act to prevent the spring 12 from pushing the holder 10 and the plunger 11 out of the upper end of the container 1. To load the container the elliptical holder 10 is pushed downwardly out of contact with the stops 15 and is slightly pivoted with respect to the plunger 11 as illustrated in Figure 7. A stack of flat nested cups 9 may now be inserted through the upper end of the open container with the lowermost cup seated upon the elliptical holder 10. The stack of cups is then pushed downwardly to compress the spring 12 and is slightly rotated to permit the edges of the uppermost cup 35 to engage in the notches provided in the guides or stops 15 as illustrated in Figures 3 and 6. The cover 6 is now closed and locked in position with the top of the uppermost cup projecting through the notched middle portion of the slot 7, as illustrated in Figure 1.

To extract a cup from the container the thumb and forefinger of an operator are placed on opposite sides of the tip of the projecting cup and the cup is pulled outwardly through the cover slot 7. As the cup is pulled upwardly the creased portion of the cup passes through the notches of the guide members 15 which serve to compress the cup to cause the sides thereof to bulge outwardly away from the cup immediately therebelow. The cup is then easily pulled through the slot in the cover 6. As soon as the open lower end of the cup passes through the cover slot the extracted cup springs into a partially open position ready to be inverted and filled.

When a cup is extracted from the upper end of the closed container the spring 12

acts automatically to push the remaining 60 stack of cups upwardly to position the next cup in place ready to be grasped by the fingers of a person desiring to use the next cup. The cups are thus automatically fed upwardly in the container by means of the 65 spring 12 each time a cup is withdrawn through the slotted cover.

I am aware that many changes may be made and numerous details of construction may be varied through a wide range without departing from the principles of this invention, and I therefore do not purpose limiting the patent granted hereon, otherwise than necessitated by the prior art.

I claim as my invention:

1. A nested flat cup dispenser of the class described, comprising a container, means thereon for mounting the same, a cover on said container having a slot and notches therein, notched cup guides within said container, a cup holder adapted to support a stack of flat nested cups in inverted position, and spring means supporting said holder and adapted to resiliently support the stack of cups so that the tip of the uppermost cup is projected through the cover slot between the cover notches ready to be withdrawn from the container.

2. In a flat nested cup dispenser of the class described the combination with a container of substantially elliptical cross section, of a slotted elliptical conical cover pivotally mounted on said container, means for removably locking the cover in closed position, and a spring impelled holder slidably mounted within the container adapted to support a stack of flat nested cups in position with the tip of the uppermost cup projecting through the slotted cover.

3. In a flat nested cup dispenser of the class described the combination of an elliptical container, of an elliptical frustum shaped cover movably mounted on said container, said cover having a slot and notches therein, oppositely disposed notched guides supported within said container, a plunger slidably mounted within said container, a cup holder pivotally mounted on said plunger, and a spring supported within the container below the plunger to support the plunger and feed said holder upwardly through the container to feed a stack of cups between said notched guide members into said slotted cover for removal from the container one at a time.

In testimony whereof I have hereunto subscribed my name.

CESARE BARBIERI.
